US00D671409S

(12) **United States Design Patent**
Cohen et al.

(10) **Patent No.:** **US D671,409 S**
(45) **Date of Patent:** **** Nov. 27, 2012**

(54) **CONTAINER**

(75) Inventors: **Erica Eden Cohen**, New York, NY (US); **Nathaniel Giraitis**, New York, NY (US); **Jonathan Mandell**, Gurnee, IL (US); **Nicolas Oxley**, New York, NY (US); **Jacob Palmborg**, Brooklyn, NY (US); **Jessi Pervola**, Brooklyn, NY (US); **Richard Whitehall**, New York, NY (US)

(73) Assignee: **S. C. Johnson & Son, Inc.**, Racine, WI (US)

(**) Term: **14 Years**

(21) Appl. No.: **29/422,412**

(22) Filed: **May 21, 2012**

Related U.S. Application Data

(62) Division of application No. 29/408,154, filed on Dec. 7, 2011, now Pat. No. Des. 663,618, and a division of application No. 29/379,398, filed on Nov. 18, 2008, now Pat. No. Des. 652,319.

(51) **LOC (9) Cl.** **09-01**

(52) **U.S. Cl.** **D9/500**

Primary Examiner — Catherine Tuttle

CLAIM

(57) The ornamental design for a container, as shown and described.

DESCRIPTION

FIG. 1 is an isometric view of the top, front, and right side of the container;

FIG. 2 is a front elevational view of the container of FIG. 1, the rear, right side, and left side elevational views of such container being identical thereto;

FIG. 3 is a top plan view of the container of FIG. 1; and, FIG. 4 is a bottom plan view of the container of FIG. 1. The broken lines are included for the purpose of illustrating portions of the container that form no part of the claimed design.
